ELECTRIC COUPLING FOR THE OPERATION OF X-RAY TUBES OR OTHER THERMIONIC TUBES

Gotfred Borge Davidsen, Hareskovby, Denmark

Application June 30, 1954, Serial No. 440,481

Claims priority, application Denmark March 26, 1954

3 Claims. (Cl. 250—103)

The invention relates to an electric coupling for the operation of X-ray tubes or other thermionic tubes having an incandescent cathode and an anode, and two transformers the secondary windings of which provide the tube with high tension, at least one of the said transformers having a winding for supplying filament current to the incandescent cathode of the tube, the primary windings of the said transformers having a common point, while the outer terminals of the said windings lying at the greatest distance of the common point are connected to a regulating transformer, and of the kind having regulating means for the high tension and filament current of the tube.

Electric couplings of the aforesaid kind are known, but the regulating means which are inserted in the coupling are frequently rather complicated and consequently less reliable in operation, adding substantially to the manufacturing cost of the installations in which they are used and the cost of operating these installations. In addition, the regulating means involve a substantial increase in weight and dimensions of the apparatus provided with the coupling, thereby reducing their applicability in portable installations and under unfavourable conditions of space.

The aforesaid drawbacks are eliminated in an electric coupling in accordance with the invention thereby that the common point is connected to a tapping point on the regulating transformer of the coupling, the distances from the said tapping point to the points of connection between the said outer terminal and the regulating transformer being adjustable.

As a result, both the high tension and the filament current supplied to the tube may be regulated within wide, predetermined limits, as a variation of the distance between the outer terminal of the first transformer having a winding for supplying filament current and the tapping point causes a variation in high tension and filament current alike, whereas a variation in the distance between the outer terminal of the second transformer and the tapping point solely causes a variation in the high tension.

In one embodiment in accordance with the invention the tapping point consists of a sliding contact resting against a stripped part of the winding of the regulating transformer, or against contact pieces connected to the wires of the said winding.

As a result, the distance between the outer terminal of the first transformer and the tapping point may be increased or reduced, whereby the high tension originating from the first transformer is increased or reduced, the high tension originating from the second transformer being simultaneously reduced or increased, respectively.

In another embodiment in accordance with the invention in which the one outer terminal of one of the transformers is connected to a sliding contact, the two sliding contacts are disposed each in a separate plane at right angles to the wires of the windings of the regulating transformer and may be adjusted independently of each other.

2

As a result, the two sliding contacts may pass by each other along the windings of the regulating transformer, whereby the high tension originating from the second transformer may be used, for instance, to counteract the high tension originating from the first transformer, and the resulting high tension may therefore be reduced to a value lower than that corresponding to the adjustment of the sliding contact at the tapping point.

In a third embodiment in accordance with the invention the outer terminals are each connected with their separate sliding contact which rests against a stripped part of the winding of the regulating transformer, or against contact pieces connected to the wires of the said winding.

As a result, the sliding contacts may be disposed in the same plane so that the regulating transformer may be made of lower height, whereby a further economy of space is obtained.

The invention will now be described in detail with reference to the drawing, in which:

Figure 1 shows an embodiment of an electric coupling according to the invention, connected to an X-ray tube;

Figure 2 is another embodiment of the said coupling;

Figure 3 is a perspective view of a coil having a stationary tap and a pair of movable contacts arranged to pass each other;

Figure 4 is a view similar to Figure 3, but with the fixed tap so arranged that at least one contact is movable past said tap; and

Figure 5 is a view similar to Figures 3 and 4, but with the two contacts arranged to operate in a common plane.

An electric coupling in accordance with the invention consists of an X-ray tube 1 or another thermionic tube having an incandescent cathode 2 and an anode 3 and two transformers 4 and 5 whose secondary windings supply high tension to the tube 1, at least one of the said transformers (4) having a winding 6 for supplying filament current to the incandescent cathode 2. The primary windings of the transformers 4, 5 are connected

with each other at a common point 7, whereas the outer terminals 9 and 10 of the said windings which are at the greatest distance from the common point 7 are connected to a regulating transformer 8 which is connected to power lines at terminals 11 and 12.

In accordance with the invention the common point 7 is connected to a tapping point 13 on the regulating transformer 8 of the coupling, and the distances from the said tapping point 13 to the connecting points 14, 15 of the outer terminals 9, 10 are adjustable.

In the embodiment of an electric coupling according to the invention as disclosed in Figure 1 the tapping point 13 is constituted by a sliding contact 13 resting against a stripped part of the winding of the transformer 8, or against contact pieces connected to some of the wires of the said windings. The one outer terminal 14 may in known manner be connected to a sliding contact of similar kind as that constituting the tapping point 13, and in accordance with the invention the two sliding contacts 13 and 14 are then mounted in different planes at right angles to the wires of the windings of the regulating transformer 8 and are adjustable independently of each other.

In the embodiment of an electric coupling according to the invention as shown in Figure 2 the outer terminals 9, 10 are each connected to their separate sliding contact which rests against a stripped part of the windings of the regulating transformer 8, or against contact pieces connected with some of the wires of the said windings. In order to simplify the coupling the tapping point

13 may in this embodiment be made as a permanent connection between the common point 7 and the regulating transformer 8, but alternatively it may also be pro-

vided with a sliding contact of the same kind as that described above with reference to Figure 1.

What I claim and desire to secure by Letters Patent is:

1. A regulating apparatus for thermionic tubes having an incandescent cathode and an anode, a pair of transformers for energizing the tube, at least one of said transformers having a winding for supplying filament current to said incandescent cathode, the primary windings of said transformers having a common terminal as well as a pair of exterior terminals, and a voltage regulating transformer connected to said common terminal and having a pair of contacts connected to said exterior terminals of said primary winding and having sliding contact toward and from each other over a stripped part of said regulating transformer whereby the said primary windings as occasion requires may counteract each other upon operation of said regulating transformer.

2. A regulating apparatus as claimed in claim 1 in which one of the exterior terminals of one of said primary windings is connected to a sliding contact resting

10

15

20

against a stripped part of the windings of the regulating transformer, and said common terminal is in such a way connected to a sliding contact resting against another stripped part of the windings of the regulating transformer that the two sliding contacts are movable past each other.

3. A regulating apparatus as claimed in claim 1, wherein in said common terminal is connected to a stationary tap on the winding of the regulating transformer, characterized in that said stationary tap is situated at a distance from both of the ends of the said regulating transformer winding in such a way that at least one of the sliding contacts is movable past the tap.

Notice of Adverse Decision in Interference

In Interference No. 90,076 involving Patent No. 2,838,934, G. B. David-
sen, Electric coupling for the operation of X-ray tubes or other thermionic
tubes, final judgment adverse to the patentee was rendered Oct. 18, 1961, as to
claims 1 and 2.
